UNITED STATES PATENT OFFICE.

ALEXANDER E. KEITH, OF HINSDALE, ILLINOIS.

GAS-COMPRESSING OR GAS-CIRCULATING SYSTEM AND APPARATUS FOR USE THEREIN.

1,171,959.

Specification of Letters Patent. Patented Feb. 15, 1916.

Application filed March 25, 1912, Serial No. 686,069. Renewed July 3, 1915. Serial No. 37,951.

To all whom it may concern:

Be it known that I, ALEXANDER E. KEITH, a citizen of the United States of America, and resident of Hinsdale, DuPage county, Illinois, have invented a certain new and useful Improvement in Gas-Compressing or Gas-Circulating Systems and Apparatus for Use Therein, of which the following is a specification.

10 My invention relates to gas compressing or circulating systems, in which the compression or circulation is obtained in any suitable manner, as by the use of a compression pump, or in which the pressure is obtained by the combustion of some material, as in the case of an internal combustion engine.

15 My invention also relates to a special valve for use in the system when the pressure is obtained by combustion.

20 Among the objects of my invention are the following: to provide a valve for an air-compressing or circulating system, which prevents leakage by maintaining the valve 25 below a non-gaseous fluid; to provide a gas-compressing or circulating system in which the gas may be generated and compressed by the combustion of any suitable material; to provide an improved valve for use in a system 30 of the above character in which the pressure is produced by combustion; to provide means between the combustion chamber and the valve for protecting the valve; and to provide certain details and features of 35 improvement tending to increase the efficiency and serviceability of a gas-compressing or circulating system and apparatus applicable for use therewith.

40 To the foregoing and other useful ends my invention consists in matters hereinafter set forth and claimed.

45 In the accompanying drawings Figure 1 represents a gas-compressing or circulating system and shows the point at which the improved valve may be inserted. Fig. 2 shows a section of said valve. Figs. 3 and 4 show screens that may be used for protecting the valve.

50 In the drawings like characters refer to like parts.

Referring to Fig. 2 the cylinder A consists of a cup B, a cap C, and the terminal D. Within the cylinder there is a valve E provided with a pin F. Over the valve 55 there is a perforated screen G. This screen is held in place by a spring H, which latter

is compressed by the cap C. The valve E is held normally in its seat by the spring I, which latter is compressed by the spring H. The valve is covered by any suitable non-gaseous or liquid material J. The screen G is made tall enough to rise above the surface of the liquid, as indicated. The valve may be placed in the line at any point between the point of compression N and the reservoir O. (See Fig. 1). The end D of the cylinder A is connected to the intake line and the pipe K is connected to the reservoir. When the pressure in the intake pipe becomes sufficiently high to raise the valve E, the gas passes first directly into the portion 60 of the liquid within the screen G and then through the apertures of the screen into the upper part of the chamber. The object in providing the screen is to check the violent 65 action of the liquid due to the passage of air, and prevent the liquid being carried up to and through the pipe K. This action may be further controlled by the valve L, by means of which latter the size of the outlet 70 is regulated. By making the outlet small the pressure in the upper part of the chamber A is increased and the stream passing into pipe K becomes more constant.

If desired, the springs H and I may be 75 provided with any suitable tension regulators. When the valve is used in connection with an internal combustion engine or other similar gas and pressure generator, there is provided in the intake line a fire and heat 80 screen, such as shown in the terminal D. This screen may be made up of one or more perforated disks or plates M. (See Figs. 3 and 4.) These plates may be made to any 85 suitable thickness and perforated in any suitable manner. If desired, the screen may be made of a single plate and I don't limit myself to any particular character of screen. With the construction described a gas pipe 90 valve may be obtained. This valve may be 95 placed in the intake line at any point and the screen may be placed at any point between the pressure generator and the valve.

What I claim as my invention is:

1. The combination of a valve and a non-gaseous fluid for covering the valve and a porous screen on the intake side of the valve and one on the outlet side.
2. The combination of a valve, a screen over the valve and over a volume of a non-gaseous fluid, the latter being sustained by the valve, a source of gas supply connected 110

to the valve for operating the valve and for blowing the fluid away from the valve-opening while the gas is passing, said screen operating to restrict the ebullition of the fluid.

3. The combination of a volume of a non-gaseous fluid, a valve beneath the fluid, a source of gas supply connected to the valve, a gas chamber over the fluid for receiving the gas after it passes through the valve and fluid, an outlet from said chamber restricted in size to prevent a too rapid exit of the gas from the chamber, and to prevent also the fluid being carried over with the gas.

4. The combination of a combustion chamber for supplying gas under pressure, a valve, a pipe line connected to the chamber and the valve, and a heat screen between the chamber and the valve.

5. The combination of a combustion chamber for supplying gas under pressure, a valve, a pipe line connected to the chamber and the valve, and a perforated plate acting as a heat screen between the chamber and the valve.

6. The combination of a combustion chamber for supplying gas under pressure, a valve, a pipe line connected to the chamber and the valve, and a perforated plate serving as a fire screen between the chamber and the valve.

7. The combination of a combustion chamber for supplying gas under pressure, a valve, a volume of non-gaseous fluid resting over said valve, a pipe line connected to the chamber and the valve, and a heat screen between the chamber and the valve.

8. The combination of a volume of a non-gaseous fluid, a valve beneath the fluid sustaining the latter, a source of gas supply connected to the valve for operating the latter and preventing the fluid from passing toward the source of gas, said source of gas

being supplied by combustion of suitable material, and a heat and fire screen interposed between the source of gas supply and the valve.

9. The combination of a valve, a screen over the valve and over a volume of a non-gaseous fluid, the latter being sustained by the valve, a source of gas supply connected to the valve for operating the valve and for blowing the fluid away from the valve-opening while the gas is passing, said screen operating to restrict the ebullition of the fluid, said source of gas being supplied by combustion of suitable material, and a heat and fire screen interposed between the source of gas supply and the valve.

10. The combination of a volume of a non-gaseous fluid, a valve beneath the fluid, a source of gas supply connected to the valve, a gas chamber over the fluid for receiving the gas after it passes through the valve and fluid, an outlet from said chamber restricted in size to prevent a too rapid exit of the gas from the chamber, and to prevent also the fluid being carried over with the gas, said source of gas being supplied by combustion of suitable material, and a heat and fire screen interposed between the source of gas supply and the valve.

11. The combination of a valve, a chamber containing the valve, a non-gaseous fluid resting on the valve, and a screen over the valve.

12. The combination of a valve, a chamber containing the valve, a non-gaseous fluid resting on the valve, and a perforated screen over the valve.

Signed by me at Chicago, Cook county, Illinois, this 8 day of March, 1912.

ALEXANDER E. KEITH.
